[57] CLAIM

The ornamental design for a crepe maker, as shown and
described.

DESCRIPTION

FIG. 1 is a perspective view of a crepe maker embodying
my new design;

FIG. 2 is a top plan view thereof;

FIG. 3 is a side elevational view thereof, the opposite
side being a mirror image of same;

FIG. 4 is a front end view thereof; and

FIG. 5 is a rear or handle end view thereof.

Fig. 1.

Fig. 2.

Fig. 3.

Fig. 4.

Fig. 5.
